HEARTH CONSTRUCTION FOR ROTARY OIL
BURNERSMilton A. Powers, Detroit, Mich., assignor to The
Timken-Silent Automatic Company, Detroit,
Mich., a corporation of Michigan

Application February 18, 1932, Serial No. 593,741

13 Claims. (Cl. 158—4)

My invention relates to hearth construction for rotary oil burners, particularly rotary burners of the type wherein both ignition and combustion take place adjacent to a wall or hearth ring disposed around the periphery of the hearth. The invention has for its principal object a hearth construction that provides a protected zone for initial ignition of the fuel and propagation of the flame around the entire periphery of the hearth and which, at the same time, provides a sufficient draft and supply of air around the entire hearth to support combustion after initial ignition and propagation of the flame.

This application is a continuation in part of my application Serial No. 324,817, filed December 10, 1928, for Rotary oil burner and combustion chamber therefor.

The invention consists principally in providing a rib or wall around the periphery of the hearth, and in providing said wall with an inwardly overhanging ledge or flange, forming a protected annular space for ignition and propagation of the flame. A further modification of the invention consists in providing said ledge with a multiplicity of recesses or openings through which the air draft passes, such recesses preferably extending not more than half the distance from the front or inner edge of said ledge to the upstanding wall or rib.

The invention further consists in the hearth for rotary oil burners and in the parts, and combinations, and arrangements of parts hereinafter described and claimed.

In the accompanying drawings, which form part of this specification and wherein like symbols refer to like parts wherever they occur,

Fig. 1 is a vertical sectional view of a rotary oil burner and combustion chamber therefor, having a hearth construction embodying my invention,

Fig. 2 is a similar view of a modified form of hearth construction showing also a different form of distributor head, and

Fig. 3 is a detail view of a further modified form of hearth.

The hearth construction may be used with any desired form of distributor head and burner construction, the drawings illustrating in Figure 1 the burner construction shown in my said prior application Serial No. 324,817, and in Figure 2 a modified alternative form. In this construction, a suitable base 1 provided with adjustable legs 2 has mounted thereon a frame member 3 on which is mounted a stationary electric motor field member 4 with its winding 5. A frame member 6 above said field has a flat top portion and a de-

pending flange portion 7 to which is secured the electric motor armature 8. Electric wires 9 in a cable 10 are connected to the field winding 5 and the usual contact making and breaking mechanism 11 is provided for split phase motor starting purposes.

The armature support 6 is provided with a tubular sleeve 12 that extends axially through bearings 13 in the field supporting frame 3 and into the base, its lower end being supported on an anti-friction step bearing 14.

Secured to the armature support 6 at its top is a hollow shaft 15 at whose upper end is secured a fan or blower 16. The fan comprises a housing whose top or back portion is preferably cupped or dished and which has depending blades 17 terminating in an end ring 18. A cylindrical sleeve 19 has a hub portion 19a secured to said hollow shaft by a set screw 20, said sleeve extends into the fan in contact with the inner edges of the fan blades 17 and thus provides means for varying the amount of air admitted to the fan. Vertical adjustment of the sleeve 19 varies the fan capacity. The connections between the sleeve 19 and the hub 19a are so small as to offer only the slightest resistance to air passing through the sleeve.

An oil feed pipe 21 mounted in the base opens into an oil passageway 22 in said base that is connected to an oil supply pipe 23. Said feed pipe 21 extends through the sleeve 12 of the armature support 6 and through the hollow shaft 15 at the top of said support, and has openings 24 at its top permitting the escape of oil. Below said openings 24 is a ring 25 that extends radially beyond said shaft, thereby preventing the escape of oil into the motor.

The oil reservoir (not shown in the drawings) is preferably above the level of the burner, so as to dispense with the need for the usual pump. Oil flows from the feed pipe 21 onto the dished back of the air fan 16, whose rotary movement throws the oil outward into the combustion chamber. Said chamber is provided with hearth structure or assembly comprising a floor or hearth proper of refractory material 26 and around the outer periphery of the combustion chamber is a wall 27 of refractory material having an inwardly projecting overhanging flange or ledge 28, so that a protected annular chamber 29 is provided around the edge of the combustion chamber. In this protected chamber, the flame is propagated; and a suitable ignition device, illustrated as a gas pilot 30, is provided adjacent thereto. In the form illustrated in Figure 1, the hearth is designed with

an upwardly and outwardly sloping surface adjacent the ignition pilot 30, which surface assists in preventing the blast of air from being projected directly into the protected chamber, as is obvious.

The overhanging ledge 28 of Figure 1 may be provided with vertical openings at intervals, if desired.

As shown in Fig. 2, the ledge 28 may be provided around its inner periphery with notches or recesses 28a which notches preferably extend not more than half the distance from the inner edge of said ledge to the upstanding wall 27. The distributor head of this view includes tubes 50 from which oil is thrown in streams between fan blades 51 that create the air draft.

In the further modification shown in Figure 3, a groove 26a is provided in the hearth floor 26 around the base of the wall 27 and the ledge 28 is provided with vertical openings 28b therethrough.

The oil spray from the burner head strikes against the wall 27 under the ledge 28, forming a mist. The air stream is caused to move upwardly over the ledge 28, by reason of the blanketing effect of said ledge, and by virtue of the sloping surface formed on the hearth inwardly of the igniter 30, leaving the air and fuel in the recess comparatively undisturbed. This results in quick ignition and quick propagation of the flame around the entire periphery of the hearth. After this propagation of the flame and as the temperature of the hearth rises, the flame moves inwardly and upwardly over the edge of the ledge and later a large volume of flame is concentrated above the ledge.

It may be desirable to provide for recirculation of the gases in the combustion chamber. In such case, a second fan member 31 is disposed above the air supply fan and secured thereto by suitable pins 32. The recirculation fan 31 rotates with the air supply fan 16 and causes circulation of the partly consumed gases in the combustion chamber, thereby bringing about a more nearly complete combustion of the fuel. The recirculation fan projects above the level of the overhanging ledge so as to draw partly consumed gases from above the level of the annular chamber.

A suitable magnetic control valve, whose housing 33 is shown in the drawings is provided to shut off the flow of fuel when the current to the motor is shut off. Said valve is of standard construction and is not shown in detail in the drawings. Likewise, any suitable control system may be used and no such system is shown in the drawings.

The above described hearth construction reconciles the conflicting requirements of a protected ignition and propagation zone and a complete draft and supply of air for the working flame, said flame not being confined to the limited propagation zone. Although it is illustrated in connection with two types of burner heads and motor constructions, it will be understood that it is applicable to other types as well. The overhanging ledge provides a protected zone for ignition and propagation of the flame. At the same time, the completed flame is free to project inwardly and upwardly over the ledge, where a complete supply of air is provided by a draft from the fan. As the hearth becomes more and more heated, the final working flame will be largely concentrated above the ledge. The ledge serves as a flame retention member to prevent it from lifting too far off the hearth and as a heat conducting member to transmit heat to the wall 27, thus causing the oil to be

vaporized quickly. The flame controlling and retaining function is enhanced by the use of the vertical openwork described above, whether said openwork be in the form of notches 28a as in Figure 2 or of endless holes 28b as in Figure 3. 5

Obviously numerous changes may be made in the sizes and proportions of the various parts and I do not wish to be limited to the precise construction shown.

What I claim is:

1. An oil burner construction comprising a combustion chamber having a hearth of refractory material, a continuous wall extending around the periphery of said hearth, a ledge having an imperforate portion projecting inwardly from the upper portion of said wall and materially overhanging the hearth, and rotary means for spraying oil into said combustion chamber below the level of the overhanging portion of said ledge member. 15

2. An oil burner construction comprising a combustion chamber having a hearth of refractory material, an imperforate wall of refractory material extending around the entire periphery of said hearth, a ledge member having an imperforate portion of refractory material projecting sufficiently inwardly from the upper portion of said wall to materially overhang said hearth and means for spraying oil into said combustion chamber below the level of the overhanging portion of said ledge member. 25

3. An oil burner construction comprising a combustion chamber having a hearth of refractory material, a continuous wall of refractory material extending around the periphery of said hearth and having a continuous inwardly extending ledge merging directly into its top overhanging the entire periphery of the hearth, and means for spraying oil into said combustion chamber below the level of the overhanging portion of said ledge member. 35

4. In a liquid fuel burning apparatus, a substantially horizontal hearth, an upright wall mounted upon the hearth, a fuel and air projector disposed just above the hearth level in spaced relation to said wall to throw fuel into impingement with said wall, and a substantially horizontal ledge provided with an imperforate roof portion, said roof portion forming with said wall a substantially continuous and unbroken surface 50 that projects away from the wall materially in the direction of said fuel and air projector; whereby said hearth, said wall and said roof portion cooperate to form a protected zone for initial flame propagation. 55

5. The apparatus defined in claim 4, said ledge having a conterminous edge portion extending beyond said imperforate roof portion in the direction of the projector and provided throughout its length with vertical openings, whereby said ledge serves to hold the propagated flame down toward the hearth. 60

6. In a liquid fuel burning apparatus a combustion chamber having a hearth structure and a rotary fuel and air distributor mounted substantially at the center of the hearth structure said hearth structure including a peripheral structure arranged relatively remote from said distributor and at approximately the same level, said peripheral structure having an upright fuel impact wall and forming a sheltered ignition zone, and said hearth structure being provided with a sloping surface adjacent said wall, the degree of slope being such that if the surface were projected outwardly it would intersect the pe- 70

ripheral structure adjacent the top of said sheltered ignition zone.

7. In a liquid fuel burning apparatus a substantially horizontal hearth structure having a 5 floor, an upright wall mounted upon the floor and a fuel and air projector located just above the floor in spaced relation to said upright wall, for projecting fuel into impingement with said wall and for projecting a blast of air along the floor 10 surface toward said wall, said hearth structure being provided with a gutter at the bottom of said upright wall, and a flame-controlling structure adjacent the top of said wall and overhanging said gutter; the floor surface being relatively 15 smooth and without abrupt changes in shape, and comprising a substantially flat portion terminating at the top of said gutter.

8. In a liquid fuel burning apparatus a combustion chamber having a hearth, and a rotary fuel 20 and air distributor mounted substantially at the center of said hearth to create a flow of fuel and air adjacent the hearth toward the hearth periphery; a peripheral structure on the hearth surrounding said distributor in substantially 25 radially spaced relation thereto, said structure having an upright fuel impingement wall, and means cooperating with said wall to form a substantially annular sheltered flame propagation zone, said sheltered zone being located adjacent 30 the vertex of the angle formed between said impingement wall and the hearth surface.

9. In a liquid fuel burning apparatus a combustion chamber having a distributor arranged approximately at the center of the bottom of said 35 chamber and projecting blasts of liquid fuel and air substantially horizontally, in radial direction; a hearth assembly closing the bottom of said chamber and including a fuel impingement wall outwardly spaced from said distributor; said 40 assembly further including an air deflecting surface located inwardly from said impingement wall and cooperating with the latter to form an elongated peripheral sheltering zone that is protected 45 from the air blast, and an ignition device having a flame-producing portion located within said sheltered zone between said deflecting surface and the lower portion of said impingement wall.

10. An oil burner construction comprising a combustion chamber having a hearth of refractory material, a continuous wall of refractory

material extending upwardly and around the entire periphery of said hearth, a continuous ledge member of refractory material projecting inwardly from the upper portion of said wall and overhanging said hearth to form with said wall 5 and said hearth a three-sided sheltered chamber, the inner edge portion of said ledge comprising an open-work structure, and means for spraying oil into said combustion chamber below the level of the overhanging portion of said ledge member. 10

11. An oil burner construction comprising a hearth of refractory material, a continuous wall of refractory material extending upwardly and around the periphery of said hearth and having a continuous ledge extending inwardly above the 15 hearth periphery, said hearth having a peripheral groove at the base of said wall underneath said ledge, and means for spraying oil toward said wall below the level of said overhanging ledge.

12. In a liquid fuel burning apparatus, a substantially horizontal hearth structure having an upper surface and including an upright wall mounted above said surface, a fuel and air projector located just above said surface in spaced relation to said upright wall, for projecting fuel 25 into impingement with said wall and for projecting a blast of air along said surface toward said wall, said surface having an upwardly, outwardly sloping portion disposed inwardly from said upright wall, and an ignition device having a 30 flame-producing portion disposed below the outward extension of said sloping portion of said surface and adjacent the bottom of the upright wall.

13. In a liquid fuel burning apparatus, a combustion chamber, a distributor disposed substantially centrally of the chamber and constructed to project liquid fuel outwardly and to discharge an air blast outwardly below the projected fuel, an upright impingement wall located outwardly from 40 said distributor in the path of the projected fuel, an igniting device located near the bottom of said impingement wall to cause initial flame propagation when the apparatus goes into operation, and means cooperating with said upright wall to 45 form a circumferentially elongated sheltered ignition and flame propagation zone in proximity to the bottom of said wall.

MILTON A. POWERS. 50
